UNITED STATES PATENT OFFICE.

GEORGE G. BAILEY, JR., AND JAMES GILBERT, OF BOSTON, MASSACHUSETTS.

DESIGN FOR PRINTING-TYPE.

SPECIFICATION forming part of Design No. 12,910, dated May 2, 1882.

Application filed October 21, 1881. Term of patent 14 years.

To all whom it may concern:

Be it known that we, **GEORGE GARDNER BAILEY, Jr., and JAMES GILBERT**, both citizens of the United States, residing at Boston, in the county of Suffolk and State of Massachusetts, have invented and produced a new and original Design for Printing-Types, of which the following is a specification, reference being had to the accompanying drawing, forming part thereof, in which are given the capitals and the lower-case letters, also the numerals and finals.

The characters presented by our new type are of the script kind, and the capitals and fig-

ures are furnished with flourishes to make them more nearly resemble a hand-written character. The body-lines are somewhat heavier than the connecting-lines, causing the characters printed to look more like a manual production.

We call the types "Upright Script."

We claim—

The design in printing-types presented, all substantially as shown and described.

GEORGE GARDNER BAILEY, JR.
JAMES GILBERT.
